UNITED STATES PATENT OFFICE.

ADA E. MILDEBERGER, OF BROOKLYN, NEW YORK.

SPOOL-HOLDER.

SPECIFICATION forming part of Letters Patent No. 781,217, dated January 31, 1905.

Application filed August 17, 1904. Serial No. 220,995.

To all whom it may concern:

Be it known that I, ADA E. MILDEBERGER, a citizen of the United States, residing at No. 58 Franklin avenue, borough of Brooklyn, in the county of Kings and State of New York, have invented new and useful Improvements in Spool-Holders, of which the following is a specification.

My invention relates to spool-holders adapted for use upon a work-table, upon a sewing-machine, whether the spool-spindle of the machine be vertical or horizontal, or upon a tape or the like by which it is suspended from the neck or garments of the wearer. It involves a peculiar cage-like spool-containing box provided with a hinged cover and with expandable vertical and horizontal sleeves to fit upon a machine-spindle or to prevent the cage from rolling upon a plane surface.

In the accompanying drawings, Figure 1 is a side elevation, partly in section, of the box, the spool being shown therein in dotted lines. Fig. 2 shows the same box looking from the right in Fig. 1. Fig. 3 is a section on the line 3 3, Fig. 1.

In the figures, A represents a cylindrical box having a plane bottom B and a cover C, the latter being hinged at D and provided upon the opposite side with a spring-catch E, engaging a projection F on the body of the box. The hinge consists of a closed wire loop G, having one side fixed to the cover and the other revolvably held in a bearing H below the cover and upon the outer side of the box. Below the hinge is a slightly-conical sleeve I, preferably consisting of a spirally-wound piece of sheet metal having one side fixed to the box, as by soldering, for example, one margin at least being free, so that the internal diameter may be varied by winding or unwinding adjustment. Below this sleeve is a second similar sleeve J, fixed to the box in a vertical position with its smaller end uppermost. The body of the box is provided with wide vertical slots K, extending nearly from top to bottom, but not wide enough to allow any ordinary spool to pass, though wide enough so that the spool within is distinctly visible, whereby its size, color, and condition as to

quantity of thread remaining may be known without opening the box. The interior of the box is materially larger than the corresponding dimensions of any ordinary spool, and the lateral margins of the slots are rounded and roughened, so that they afford a frictional surface upon which the peripheral surface of the spool ends will not easily slip. Upon the bottom of the box normally rests a loose disk L, preferably having its upper surface of a friction-producing character—for example, felt-like. Ordinarily the box is used in erect position, and the spool within it being usually too large to assume a crosswise position is also erect. There is no spindle for the spool, either above or below, upon which the thread unwound from the spool, but not drawn out, may become fast; but in any case the slight friction upon the lower end surface of the spool prevents momentum from causing any material unwinding, especially if the thread pass out upon the side most distant from the point where it leaves the spool, for in that case the peripheral surface of the spool is drawn against the roughened margin of one of the slots. If the box be in horizontal position, the unwinding pull upon the thread tends to roll the spool up one side of the box, and hence gravity resists momentum and prevents serious unwinding. If the spool be small, so that it may lie transversely in the erect box, the disk is first removed, the spool dropped in, and the inverted disk is placed upon the spool, where its frictional resistance under the weight of the disk, which may be as great as is desired, proves quite adequate to prevent the undesired rotation. It is obvious that the disk may in like manner be placed upon any large or small erect spool or ball of thread. The sleeves may be compressed to fit a small spindle or may be pressed upon a much larger spindle, the construction described evidently making this quite possible. When the box rests upon a table or the like, the two sleeves form a T-like base, preventing the box from rolling, even when thread is being drawn from it, and it is therefore very useful for such employment. If the box is to be attached to the person, so that the thread may always be conven-

iently at hand when the user is moving from place to place, a ribbon or tape may be passed through the upper tube and be pinned to the clothing or passed about the neck.

5 What I claim is—

1. As a spool-holder, a box provided with lateral openings for the passage of the thread and having on one side and in the same plane a longitudinal spindle-sleeve and a transverse 10 spindle-sleeve, substantially as set forth.

2. The combination with a spool-holding box of a depth greater than the vertical dimensions of the spool to be placed therein, of a weight having a frictional surface, loosely 15 fitting in the box, and adapted to be placed

above or below a spool, in the box, to retard the rotation of the spool.

3. The combination with the cylindrical box having the hinged cover and the lateral slots with roughened margins, of the two spindle-sleeves in the same plane, and the heavy internal loose disk. 20

In testimony whereof I have signed this specification in the presence of two subscribing witnesses.

ADA E. MILDEBERGER.
